UNITED STATES PATENT OFFICE

162,985

LIQUID SERVING UNIT

Joseph F. Punzak, Brooklyn, N. Y., assignor to
United Metal Goods Manufacturing Co., Inc.,
Brooklyn, N. Y., a corporation of New York

Application April 25, 1949, Serial No. 2,247

Term of patent 7 years

(Cl. D44—15)

To all whom it may concern:

Be it known that I, Joseph F. Punzak, a citizen of the United States, residing at Brooklyn, in the county of Kings and State of New York, have invented a new, original, and ornamental Design for Liquid Serving Unit, of which the following is a specification, reference being had to the accompanying drawing, forming part thereof.

Fig. 1 is a perspective view of a liquid serving unit, showing my new design, with the top in raised position and partly broken away.

Fig. 2 is a side elevational view thereof, on a smaller scale, with the top in closed position.

I claim:

The ornamental design for a liquid serving unit, as shown and described.

JOSEPH F. PUNZAK.
